UNITED STATES PATENT OFFICE.

JACQUES PERL, OF BERLIN, GERMANY.

AUTOMATIC GAS-IGNITER.

SPECIFICATION forming part of Letters Patent No. 627,654, dated June 27, 1899.

Application filed July 27, 1897. Serial No. 646,122. (No model.)

To all whom it may concern:

Be it known that I, JACQUES PERL, a subject of the King of Prussia, German Emperor, and a resident of Berlin, Kingdom of Prussia, German Empire, have invented certain new and useful Improvements in Automatic Gas-Igniters, of which the following is an exact specification.

This invention refers to automatic gas-igniters of the kind in which the ignition is effected by means of a small ball, disk, or the like containing finely-divided platinum or another metal of the platinum group. This ball or disk when coming in contact with the gas begins to glow and causes thus the ignition of the gas. In consequence, however, of said ball or disk remaining in the burning gas or in the flame, respectively, the aforementioned property of the finely-divided platinum to become glowing when coming in contact with the gas soon ceases, and the ball or disk in question can thus be used only for a short time or must after a short time be replaced by a fresh one. To do away with this drawback, a construction has been devised in which the platinum ball ignites an auxiliary flame, which then in its turn ignites the main flame, whereafter the auxiliary flame is automatically extinguished. Thus in this construction the platinum ball is removed from the intense heat of the main flame; but the construction working in said way is complicated and gets easily out of order. I have attained the desired effect by means of a very simple device, one form of construction of which is shown as an example in the accompanying drawings, wherein—

Figure 1 illustrates a sectional elevation of a burner provided with my improvements. Fig. 2 is a plan view of Fig. 1, the chimney being in section.

This device may be regarded in a sense as an inversion of the construction before mentioned in that I do not move the flame away from the platinum ball, but the platinum ball away from the flame, or, in the case of an incandescent lamp, from the incandescent body. In the form of construction shown my novel device is applied to an incandescent lamp and the platinum ball *a* is secured to the outer end of a helix *b*, formed by a metallic strip or band composed of two different

metals. The metal having the greater extensibility is located at the outer side of the strip or band. The other or inner end of the helix *b* is fixed to a bar *c*, secured by a screw *d* to one of the chimney-carrying arms *e* of the burner. An upwardly-extending rod *f*, also fixed to the bar *c*, forms at its upper end a hook *f'*, which takes over the helix and holds the outer end of the latter, with the platinum ball *a*, in proper working position. The strip or band *b* when heated by the flame of the burner extends and, owing to said strip or band forming a helix and the outer metal being capable of a greater extensibility, the helix contracts, so that the platinum ball *a* is carried automatically into the position shown in dotted lines. In this position the platinum ball is so far distant from the flame or from the incandescent body, respectively, that its glowing capacity is not in the least impaired. The ball *a* remains active for a very long time. In the trials made up to now and still in progress a ball has already been used for more than one thousand hours of burning without having lost the least of its power.

Of course instead of forming the strip or band into a helix I may form it into a body of another shape, provided that body be able to bend, so as to move the platinum ball away from the flame.

Having thus fully described the nature of this invention, what I desire to secure by Letters Patent of the United States is—

1. In an automatic gas-lighting device, the combination with a gas-burner, of a metal strip composed of two strips arranged side by side, having different coefficients of expansion, a body *a* of finely-divided platinum carried by said strips, the two strips of metal being in such position relatively to the burner, and to each other, and so combined with the body *a*, that when the strips are subjected to the heat of the flame, the body *a* is carried out of the influence of the heat of the flame by the movement of the said metal strips, for the purpose as set forth.

2. In an automatic gas-lighting device, the combination with a gas-burner and the bearing-rod *c*, of a spiral-wound metal strip, composed of two strips of metal having different coefficients of expansion, said strip being attached at one end to the bearing-rod *c*, the

- body *a* consisting of finely-divided platinum carried by the other end of the strip, said body standing in proximity to the jet-orifice of the burner, when the flame is not burning, 5 and the two strips of metal being so arranged relatively to each other as to carry the body *a* out of the influence of the flame, after the same has been ignited, substantially as set forth.
- 10 3. In an automatic gas-lighting device, the combination with a gas-burner and bearing-rod *c*, of a spiral-wound metal strip, composed of two strips of metal, having different coefficients of expansion, said strip being attached 15 at one end to the bearing-rod *c*, a body *a* consisting of finely-divided platinum carried by the other end of the strips, said body, when

in normal position, standing in proximity to the jet-orifice of the burner and the two strips of metal being so arranged relatively to each other whereby when heated they will carry the body *a* out of the influence of the heat of the flame, substantially as set forth. 20

4. In combination with a gas-burner, an igniting substance therefor and a bimetallic 25 thermostatic connection between said burner and the igniting substance.

In testimony whereof I have signed this specification in the presence of two subscribing witnesses.

JACQUES PERL.
